(57) CLAIM

The ornamental design for a golf glove, as shown and described.

DESCRIPTION

FIG. 1 is a perspective view of the back portion of the glove.

FIG. 2 is a perspective view of the back portion of the glove; and,

FIG. 3 is a perspective view of the thumb side of the glove.

The broken lines of FIGS. 1–3 showing the glove body and finger casings are for illustrative purposes only and form no part of the claimed design.
